HARRY LYON, OF HOLBROOK, MASSACHUSETTS, ASSIGNOR TO PERLEY E. BARBOUR, OF QUINCY, MASSACHUSETTS, DOING BUSINESS AS BARBOUR WELTING COMPANY.

WELTING AND METHOD OF MAKING THE SAME.

Application filed December 23, 1926. Serial No. 156,712.

This invention relates to welting for use in the manufacture of Goodyear welt boots and shoes, and to a novel method of making the same.

5 Goodyear welting, as commonly manufactured, consists of a strip of grain leather having its grain side generously beveled at one edge and a groove formed in the flesh side near said beveled edge. These two 10 cuts are both at the inner edge of the welting when incorporated in a shoe. The bevel and groove increase the flexibility of the welting and assist in bending and fitting the inner edge thereof against the inlasted 15 upper and into the angle between the feather and sewing-rib of the insole, and the groove provides a secure anchorage for the inseam stitches and is made large enough to bury the heavy chain-stitched inseam when the 20 welt is beaten out prior to the outsole stitching operation thus presenting a smooth lower welt face for engagement by the outsole. In the manufacture of welting as 25 just described the blank strip must be of the entire overall width of the welting in its finished form and the considerable amount of stock removed by grooving and beveling becomes waste.

30 Goodyear welting requires expensive leather because its texture must be of sufficient strength to hold the shoe together under the strains during wear which affect the inseam and outseam. A highly important feature of welting is the retention of a sufficient width of grain surface because the groove is so located relative to the bevel that the curved needle of the welt sewing machine strikes through the outer edge 35 of the bevel cut, i. e. where the bevel joins the grain, thus causing the inseam to draw the grain of the welt tightly against the grain of the upper. If, in order to save stock, the width of the grain surface is skimped, as by using a narrower strip than 40 described above, then the flesh uncovered by the bevel cut will be visible at the crease of the shoe after inseaming and we have what is known as a "grinning inseam" which indicates poor shoemaking and produces "cripples."

45 The present invention provides a method of manufacture whereby the requisite width of grain surface is preserved, or even increased, and yet full width welting may be 50 produced from a strip that is considerably

narrower than the finished welting. The resultant welting has the desired bevel to promote flexibility at its inner edge and an ample width of groove, for receiving and burying the inseam stitches, due to the novel 60 shape of cut made in the flesh side and from which the groove is produced. Furthermore all of the advantages are secured with a negligible or no removal of stock from the strip, i. e. no waste, and 65 without any undesirable condensing of the stock within or about the groove or any other part of the welting which is to receive stitching.

70 For a more complete understanding of the invention reference may be had to the accompanying drawing, in which:

75 Figure 1 is a view, in perspective, of a welt strip, the dotted lines showing the proportion of stock saved in making any width of welting by practising the present method;

80 Fig. 2 is a view, in perspective, of the strip shown by full lines in Fig. 1, slit and corner-sliced on its flesh and grain sides respectively;

85 Figs. 3 and 4 are views, in cross-section, of the welting showing an intermediate and the final stage of its manufacture.

Fig. 5 is a view, in perspective, showing 90 the finished welting from its grain side;

95 Figs. 6, 7 and 8 are views, in cross-section, of a modified form in which a still narrower strip may be used, and providing for the complete bevel by bending alone, the three figures illustrating the blank strip, the fillet slit on its flesh side and the finished welting provided with a groove and bevel;

100 Fig. 9 illustrates Goodyear welting as at present manufacture, in cross-section, and by 95 the dotted lines connecting it with Fig. 8 illustrates graphically how the overall width of the narrow strip of Fig. 6 is increased to equal that of the old Goodyear while yet maintaining the requisite width of grain surface;

105 Figs. 10 and 11 are views, in cross-section, of another modified form of the welting when made from the narrow strip;

110 Figs. 12 and 13 are views, in cross-section, of welting like that shown in Figs. 7 and 8 but using a modified form of slit in the flesh side;

Fig. 14 represents a cross-section through a portion of an unbottomed shoe showing 110

the welting after inseaming but before beating; and

Fig. 15 represents a cross-section, as in Fig. 14, but with the welt beaten and an outsole stitched thereto.

Referring first to Figs. 1 to 5 inclusive which illustrate the preferred form of the welt, the welt strip 20 indicated by full lines in Fig. 1 is narrower, by the amount of stock blocked out by the dotted lines 21, than the welt strip required for the manufacture of Goodyear welting by the old method (see Fig. 9). Assuming that "half-inch" welting is to be produced, i. e. one-half of an inch over all width, then the saving of stock by the method of manufacture to be hereinafter described will run from 6½% to 12½% which, when the high cost of stock for fine grades of welting is considered, is a material saving and enables a substantial reduction in the cost per yard of manufacture. Each pair of welt shoes requires substantially a yard of welting and the usual orders for welting from shoe manufacturers are for from several hundred thousand to millions of yards. This indicates roughly the enormous saving in stock that this invention secures while yet producing welting which is the equal in all aspects of the welting made by the old wasteful method.

In the new method of manufacture the flesh side F of the strip 20 is slit longitudinally as at 22 with a knife having a blade shaped as shown on the end of the welt in Fig. 2, that is, an edge that ends its slit 23 substantially perpendicular to the flesh side and an edge that ends its slit 24 substantially perpendicular to the inner edge surface 26, said blade having preferably, but not necessarily, a formation which joins the two cuts by a curved heel 25. The portion 23 of the slit is spaced from the outer edge 28 a distance equal to that determined by the outer edge of the groove 29 (Fig. 9) in the old type of Goodyear welting, since this portion of the slit forms the outer wall of the groove in the new welting.

As a second step, although it is within the scope of the invention to perform it at the time the flesh side is incised, the grain side at the inner corner is sliced off to a slight extent by a cut 30 which extends from a line on the inner edge 26, substantially opposite the part 24 of the slit in the flesh side, to a line on the grain side which is at least as far from the outer edge 28 as the outer end of the bevel 31 (Fig. 9) on the old type of Goodyear welting. In practice the corner-slicing is so abrupt that an even wider grain surface G is retained thus amply insuring against "grinning inseams".

The inner margin about the slit is also tempered by wetting and the slit and corner-sliced strip is then fed past a plow or plows which partially open the slit 22 as

illustrated by Fig. 3. A filler such as a starch solution for stiffening or strengthening the fibres may be applied to the open groove at this stage if deemed desirable. It will be observed that the opening of the slit 22 has forced the inner edge 26 outward and toward the oblique plane of the corner-slice 30.

The final step of completely forming the stitch-receiving groove 32 and the inner edge bevel 34 (Fig. 5) is accomplished by an outward bending and pressing of the stock between the slit and the inner edge until the sliced corner 30 and the edge 26 conform to a single oblique plane at which time the bottom portion 24 of the slit is fully exposed, providing ample room for the inseam stitches, and the stock which originally lay down in the groove 32 forms its inner wall 35 (Fig. 4). In this finished welting the groove 32 and bevel 34 are positioned relatively to each other as in the old Goodyear welting and at the inseaming machine the needle will strike through the inner wall 35 of the groove and emerge just outside the bevel, sewing a seam (see Fig. 14) which insures an exposure of grain surface from the outer edge 28 inward to the shoe crease.

The modified form of the welting illustrated by Figs. 6 to 8 is made by practising the process hereinbefore described except that the corner-slicing step is omitted. In making this form of the welting the blank strip 36 may be one-eighth of an inch narrower than the blank strip that heretofore has been grooved and beveled and this width gives a thirty-second of an inch more grain surface than before in the finished welting. The same type of slit 38 is made in the same location in the flesh side and may be, as herein illustrated (Fig. 7), a true right angle. This is optional. The process hereinbefore described having been completed the product is as illustrated by Fig. 8 with a full width, stitch-receiving groove 40 and an inner-end bevel 42 produced by bending outwardly the stock between the slit 38 and inner edge of the strip which causes the inner edge to take an inclined position at an obtuse angle to the grain side corresponding in position to the bevel 31 of Fig. 9.

The dotted lines connecting Figs. 8 and 9 serve to illustrate graphically how the process produces welting of normal overall width from a narrower strip, while yet retaining the full-sized groove and bevel and preserving an ample width of grain surface. In this form of the welting no stock is removed from the strip. This is also true of the form illustrated by Figs. 12 and 13 wherein a modified flesh side slit 44 is shown. This slit 44 is produced by a knife blade shaped like the quadrant of a circle, which will suffice to produce a groove large enough

to receive the stitching since the important consideration is to produce an opening having a wide enough base to act as a secure anchorage for the stitches. The result, after 6 completing the process, is shown by Fig. 13, the slit 44 having been opened to form a groove 48 and the inner edge simultaneously bent outward from the slit until it stands oblique to the grain side and forms a bevel 10 50.

Figs. 10 and 11 show a further modification in which, as illustrated, the flesh side has been incised by a knife which produces the right-angular slit 38, but in all the modifications any one of the described slits may 15 be used. The difference in this form resides in stripping the welting stock with a curved knife so presented to the stock as to produce a slightly concave outer edge 52 and a 20 slightly convex inner edge 54. The convexity of the knife blade is sufficiently slight to retain a substantially rectangular cross-section on the strip. Completion of the process on this strip develops the groove 56 and 25 bevel 58 while at the same time increasing the overall width to produce full width welting from the narrower strip. The curved knife makes a beveling cut slightly into the grain at the point 60 (Fig. 10) but, as shown 30 by the dotted line *a—a* on Figs. 8 and 9, a bit of this grain surface may be sacrificed and still retain the full width of the grain supplied by the old Goodyear welting. The slight concavity at the outer edge will be 35 eradicated at the edge-trimming operation.

The reason for providing the slightly convex inner edge 54 on the strip is to insure a plane-surfaced bevel on welting made from the softer and somewhat punky stock which, 40 because of its lack of stiffness or hardness, tends to break, when bent outward, somewhat below the inner grain corner rather than at said corner. The slight slicing of the inner grain corner by the curved knife straightens 45 out the bevel 58 under such conditions. It is for this reason that this form or that of Figs. 1 to 5 is preferred since the corner-slicing insures a plane-surfaced bevel throughout the entire length of each hank even 50 though the characteristics of the stock varies along different portions of said length.

It will be observed that in each instance the strip from which the welting is made is of substantially less width than is required 55 to make the old Goodyear welting of the same overall width as the welting finally produced. This increase in the overall width of the original strip is accomplished by a simple outward pressing and bending 60 which displaces the material loosened by the incision in the flesh side. This bending pressure and displacement is exercised entirely on material at the flesh sides of the strip and in a direction to force the inner edge surface 65 toward the grain side. No pressure is

exerted from the grain side toward the flesh side and no part of the groove that is formed, or any other portion of the welting, is hardened or condensed by compression of the stock. Because of the fact that only simple 70 cutting and bending operations are performed the novel welting can be easily and cheaply manufactured.

Fig. 14 illustrates welting of the present invention inseamed to the upper materials 75 and insole of a welt shoe after its bevel 34 has been fitted snugly into the angle between the feather and sewing-rib of the insole. After the welt beating operation the inseam 80 trimming operation is performed as indicated by the dash line on Fig. 14, an outsole is applied and the welting is outseamed thereto. Fig. 15 illustrates this stage of the shoemaking process.

The scope of the invention claimed herein 85 is purposely limited to welting, and the method of its manufacture, of the kind having the illustrative characteristic longitudinal slit for producing a groove, supplemented by a removal of some stock from the 90 grain side of the strip at its inner corner to assist in providing a beveled inner edge when the slit is opened to expose its bottom face. Claims to the kind of welting illustrated in the drawings, and the method of 95 its manufacture, in the broader aspects of the invention will be found in applicant's co-pending application Serial No. 731,932, filed August 14, 1924.

The nature and scope of the invention having 100 been indicated, and the preferred embodiments of the welt and the method of making it having been specifically described, what is claimed as new, is:—

1. Welting for boots and shoes comprising 105 a strip of grain leather having a grain corner removed at its inner edge, a longitudinal incision near said edge extending from the flesh side inwardly and then turning toward said edge, and having the marginal portion 110 between said incision and inner edge displaced toward the grain side with the entire inner edge positioned oblique to the grain side and said incision opened to present a stitch-receiving groove.

2. Welting for boots and shoes comprising 115 a substantially rectangular strip of grain leather having a longitudinal incision near its inner edge extending from the flesh side inwardly and then turning toward said inner edge, said inner edge being slightly beveled on its grain corner, and having the flesh stock partly severed by said incision bent outwardly to open the incision and set the edge surface thereof in the plane of 120 said grain corner bevel.

3. The method of making grooved and beveled welting for boots and shoes which 125 includes longitudinally incising the flesh side of a grain leather welt strip near its 130

inner edge by a slit which extends inwardly from said flesh side and then turns toward said inner edge, removing a slight portion of the grain by a beveling cut at the inner 5 corner of the grain side, and then opening said incision to expose the base and form a stitch-receiving groove by outward displacement of the marginal stock until the inner edge surface is pressed substantially 10 into the oblique plane of said beveling cut.

4. The method of making welting for boots and shoes which comprises slitting

inwardly from the flesh side of a substantially rectangular strip of grain leather 15 longitudinally near its inner edge, tempering said slit margin, partially opening the slit, introducing a fibre stiffening solution to said partially opened slit, and then pressing the tempered and stiffened stock outwardly to open the slit and form a stitch-receiving 20 groove and displace said inner edge from its vertical relation to the grain side and set it oblique thereto.

HARRY LYON.
